Inventor
John S. Stevenson

UNITED STATES PATENT OFFICE.

JOHN S. STEVENSON, OF DETROIT, MICHIGAN, ASSIGNOR TO THE PENINSULAR CAR COMPANY, OF SAME PLACE.

BENDING-MACHINE.

SPECIFICATION forming part of Letters Patent No. 430,898, dated June 24, 1890.

Application filed October 24, 1889. Serial No. 328,084. (No model.)

To all whom it may concern:

Be it known that I, JOHN S. STEVENSON, of Detroit, in the county of Wayne and State of Michigan, have invented a new and useful 5 Improvement in Bending-Machines, of which the following is a specification.

My invention relates to bending-machines, and has for its object to provide improved devices for bending and cutting metal, as 10 hereinafter more fully set forth.

Figure 1 is a side elevation of the machine, and Fig. 2 is a top plan view of one half of the machine, the other half being exactly the same.

15 A represents the bed of the machine, on the end of which is a stationary die D, having its inner face of the shape that it is desired to give to the article to be bent.

C represents a movable die which slides on 20 ways B in the bed A, and whose face is the converse of the die D.

O represents a gear-wheel mounted on a shaft extending across the bed of the machine, which receives power from a pinion.

25 R represents a wrist-pin secured to the wheel O, and L represents a connecting-rod, one end of which is pivoted to the wrist-pin R, and the other end of which is pivoted to the movable die C.

30 M represents a lever which is rigidly secured to the wrist-pin R.

J J represent guides secured to the side of the movable die C, in which moves a sliding head I, on the end of which is fastened a knife 35 G, with its cutting-edge lying close to the side of the die C. I usually secure this knife G to the sliding head by an angle-iron H, bolted both to the head and to the knife, this permitting the knife to be adjusted to or away from

40 the side of die C, the angle-iron having slots through which the holding-bolts pass; but the knife may be fastened in any other convenient way.

F represents a guide-plate adjustably bolted 45 to the die C to support the knife G while making its cut.

E represents the article to be bent.

N represents a connecting-rod, one end of which is pivoted to the end of the lever M, 50 while the other end is pivoted to the sliding head I.

The operation of my invention is as follows: In bending articles, especially irons, the iron

(represented by E) is heated and laid across the face of the die D. The rotation of the 55 wheel O causes the wrist-pin R, acting through the connecting-rod L, to force the die C against the article E and bend it into the shape of the faces of the two dies. Ordinarily the article bent then has to be removed from the 60 machine and cut to length in a separate machine. This I avoid by the mechanism above described. At the time the wrist-pin is in the position shown in Fig. 1 the die C is firmly pressed against the die D, clamping the article 65 between the two dies. The motion of the wrist-pin R is at this time nearly at right angles with the line of the motion of the die C, so that the travel of said wrist-pin has very little effect upon said die; but as the lever M 70 is at this time in position where its motion will have its greatest effect upon the connecting-rod N the movement of said wrist-pin causes the lever M to actuate the connecting-rod N and force the sliding head I forward, 75 bringing the knives G against the ends of the article E, and thus automatically cutting it to the desired length, after which the continued movement of the wrist-pin R will withdraw the die C and permit the article E to be 80 removed and a new one put in its place.

What I claim as my invention, and desire to secure by Letters Patent, is—

1. The combination, with the movable die and actuating mechanism therefor, in a bending-machine, of a head carried by and moving on the movable die, a cutting-knife attached to said head, and means for moving the knife-carrying head on the die, substantially as described. 85

2. In a bending-machine, the combination, with a movable die and the actuating mechanism thereof, of a sliding head carried on said movable die, a knife on said sliding head, and actuating mechanism connecting said head with the die-actuating mechanism, substantially as shown and described. 90

3. In combination with a wheel O, wrist-pin R, connecting-rod L, and die C, the lever M, connecting-rod N, sliding head I, and knife G, substantially as shown and described. 95

JOHN S. STEVENSON.
